COPIER EVENT RECORDER

Claude H. Hutcheson, Jr., Fairport, N.Y., assignor to
Xerox Corporation, Stamford, Conn.

Filed Nov. 19, 1973, Ser. No. 417,463

Term of patent 14 years

Int. Cl. D16—02

U.S. Cl. D61—1 Q

FIG. 1

FIG. 3

FIG. 2

FIG. 6

FIG. 4

FIG. 5

FIG. 1 is a perspective view of a copier event recorder showing my new design;

FIG. 2 is a front elevational view thereof;

FIG. 3 is a top plan view thereof;

FIG. 4 is a right side elevational view thereof;

FIG. 5 is a left side elevational view thereof; and

FIG. 6 is a rear elevational view thereof.

I claim:

The ornamental design for a copier event recorder, substantially as shown and described.
